SLED

Bertrand R. Lesser, 24 Stonewall Lane, Mamaroneck,
N.Y., and Morton I. Thomas, Bakertown Road,
Monroe, N.Y.

Filed Mar. 23, 1964, Ser. No. 79,110

Term of patent 14 years

(Cl. D34—15)

FIG. 3

FIG. 4

FIG. 1 is a top plan view of a sled showing our new design;

FIG. 2 is a side elevational view thereof;

FIG. 3 is a front elevational view thereof;

FIG. 4 is a rear elevational view thereof; and

FIG. 5 is a bottom plan view thereof.

The essential features of our design reside in the portions shown in full lines.

We claim:

The ornamental design for a sled, substantially as shown and described.
